UNITED STATES PATENT OFFICE

PAUL MÜLLER, OF SOLINGEN, GERMANY

GUARD FOR SAFETY-RAZOR BLADES

Application filed January 15, 1929, Serial No. 332,642, and in Germany October 4, 1928.

My invention relates to improvements in safety razors with double-edged flexible blades and the invention consists of the novel construction of the blade supporting safety 5 guard.

The bearing points for the cutting edges of flexible blades of the well known guards are not placed close to the cutting edge of the blade but a little further back. Consequently there remains a little space between guard 10 and blade when screwed together ready for use, and there is the possibility that when shaving, particles of the skin are clamped in this space and are cut.

Further the extremely thin edge of this type of blades, not being properly supported at the extreme point of the cutting edge, is inclined to vibrate, especially with strong beards, it easily gives place to the reaction of 20 the numerous hairs and does not shave clean.

The prime object of my invention is to avoid these disadvantages.

For this purpose the guard is shaped like a frame without teeth, having along the sides 25 hollowed ledges, which are lower than the main top surface of the guard plate being provided with a novel safety device in form of a number of needle like bearing points which are so placed that they support the 30 edge at the extreme point and divide the whole length of the edge into small framed sections.

This serves a triple purpose.

Firstly. It makes it impossible for particles of the skin to clamp in the space between edge and guard and cause cutting of 35 the skin when shaving.

Secondly. Any vibration of the edge giving 40 place to the reaction of the hair is impossible.

Thirdly. The needle like bearing points are so small that practically the whole length 45 of the edge is free for shaving contrary to the known guards with teeth which shave only between the latter. Further ample space is now provided between guard and cutting edge for the cut particles of the hair and the lather to escape backwards.

The diagram indicates the description of 50 this invention.

Figure 1 is a perspective view of the safety guard with handle and cap.

Figure 2 is a detailed perspective view of one of the ordinary blades, commonly employed with razors of this type. 55

Figure 3 is a view of the safety razor with the blade in position thereon.

Figure 4 is a front view of the safety razor.

a shows one of the needle like bearing 60 points.

b shows the edge of the blade.

c shows the guard.

d shows the raised main top surface of the guard.

e and f show the 2 hollowed ledges. 65

g and h show the 2 apertures for the escape of the lather.

What I claim is:

In a safety razor for double edged flexible blades a frame like guard plate without teeth, said guard plate having along the sides hollowed ledges, said ledges being rounded off and lower than the main top surface of the guard plate and being provided with a novel safety device in form of needle-like bearing points, said needle-like bearing points being positioned to support a double edged flexible blade, although the edge is quite free across its whole breadth, quite immovably right up to the very cutting edges, dividing said cutting edges into small closed sections for the purpose set forth in the specification. 70 75 80 85
